UNITED STATES PATENT OFFICE.

MATHIEU BERGOUGNAN, OF PARIS, FRANCE, ASSIGNOR TO SOCIETE GENERALE DES
ETABLISSEMENTS BERGOUGNAN, OF CLERMONT FERRAND, PUY DE DÔME, FRANCE.

DESIGN FOR A VEHICLE-TIRE.

47,771.

Specification for Design. Patented Aug. 31, 1915.

Application filed April 3, 1914. Serial No. 829,376. Term of patent 14 years.

To all whom it may concern:

Be it known that I, MATHIEU BERGOUGNAN, a citizen of the Republic of France, residing at 9 Rue Villaret de Joyeuse, Paris, in the Republic of France, have invented a new, original, and ornamental Design for a Vehicle-Tire, of which the following is a specification, reference being had to the accompanying drawing, forming part thereof.

The accompanying drawing illustrates a part of the rubber tire, Figure 1 being a

cross section along lines A—A of Figs. 2 and 3,—Fig. 2 being an elevation and Fig. 3 a plan view.

I claim:—

The ornamental design for a vehicle tire as shown.

MATHIEU BERGOUGNAN.
